(57) **CLAIM**

The ornamental design for a portable electronic device carrier, as shown and described.

DESCRIPTION

FIG. 1 is a front and right side perspective view of a portable electronic device carrier in a closed position;

FIG. 2 is a front view of the portable electronic device depicted in FIG. 1;

FIG. 3 is a top view of the portable electronic device carrier depicted in FIG. 1;

FIG. 4 is a left side planar view of the portable electronic device carrier depicted in FIG. 1;

FIG. 5 is a bottom view of the of the portable electronic device carrier depicted in FIG. 1; and,

FIG. 6 is a rear view of the portable electronic device carrier depicted in FIG. 1.
